CLAIM

The ornamental design for a ceiling fan motor housing, as shown and described.

DESCRIPTION

FIG. 1 is a bottom perspective view of a ceiling fan motor housing showing my new design, shown in the environment of a ceiling fan;

FIG. 2 is a top perspective view of the ceiling fan motor housing of FIG. 1, but shown without the ceiling fan environment;

FIG. 3 is a top view thereof;

FIG. 4 is a bottom view thereof; and,

FIG. 5 is a front side view thereof, with rear, right, and left side views being mirror images thereof.

The broken lines illustrate environmental structure, and portions of the ceiling fan motor housing. None of the broken lines form part of the claimed design.
